Primary Examiner — Antoine Duval Davis(74) *Attorney, Agent, or Firm* — Bycer & Marion, PLC; Michael B. Marion; Matthew L. Bycer**CLAIM**

The ornamental design for a pipefitting square, as shown and described.

DESCRIPTION

FIG. 1 is a perspective view of the pipefitting square showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a view of the “pipe square” in use.

The broken lines in FIG. 8 showing the pipefitting square in use illustrates environment and forms no part of the claim.

1 Claim, 5 Drawing Sheets(56)
